(57) **CLAIM**

The ornamental design for a four-axis unmanned aerial vehicle, substantially as shown and described.

DESCRIPTION

FIG. 1 is a top, front and right side perspective view of a four-axis unmanned aerial vehicle, showing my new design; FIG. 2 is a top, rear and right side perspective view; FIG. 3 is a front elevational view thereof; FIG. 4 is a rear elevational view thereof; FIG. 5 is a right side elevational view thereof; FIG. 6 is a left side elevational view thereof; FIG. 7 is a top plan view thereof; FIG. 8 is a bottom plan view thereof; and, FIG. 9 is a partial enlarged view of FIG. 1.

The broken lines in FIGS. 1 and 9 illustrate the periphery of the enlarged views of a four-axis unmanned aerial vehicle and form no part of the claimed design.
